UNITED STATES PATENT OFFICE.

JOHN L. KING, OF CHICAGO, ILLINOIS, ASSIGNOR TO ROTARY KING SAFETY RAZOR COMPANY, A CORPORATION OF DELAWARE.

SAFETY-RAZOR.

1,366,468.

Specification of Letters Patent. Patented Jan. 25, 1921.

Application filed February 18, 1920. Serial No. 359,719.

To all whom it may concern:

Be it known that I, JOHN L. KING, a citizen of the United States, residing at Chicago, Cook county, Illinois, have invented 5 certain new and useful Improvements in Safety-Razors, of which the following, taken in connection with the drawings, is a description.

My invention relates to razors of the class 10 known as safety razors, and more particularly to those having a reciprocating motion of the blade, by means of which the shaving operation may be performed more quickly, easily and effectively than with razors of 15 the forms of construction now in use.

A further object of the invention is to provide a removable blade which is easily and quickly adjusted in position for use, which may be removed and replaced when 20 desired.

Further objects and advantages of my improved construction will be apparent to those skilled in the art and in the accompanying drawings I have illustrated what 25 I now consider the preferred form of my invention which consists in the construction and novel combination and arrangement of parts hereinafter described, it being understood that various changes in the form 30 portion, size and minor details of construction within the scope of the claims may be resorted to without departing from the spirit or of sacrificing any of the advantages of the invention. In these drawings:—

Figure 1 is a side elevation of my invention;

Fig. 2 is a top plan view of the razor head partly broken away;

Fig. 3 is a plan view of the razor blade;

Fig. 4 is a detail of the roller detached from the frame;

Fig. 5 is an enlarged detailed side elevation of the razor head, partly in section, 45 illustrating the adjusting mechanism.

Referring to the drawings 6 represents the handle of the razor, which may be or may not be knurled as shown. Mounted upon this handle 6, or if desired formed integrally therewith, is a supporting member 7 which is arranged upon an angle to the handle, as shown in Figs. 1 and 5. Extending transversely of one edge of this frame and preferably formed integrally therewith

are a plurality of guard teeth 8, above which 55 the razor blade is supported.

The upper face of the supporting member 7 is provided with a recess 9 extending parallel with which is a plurality of ribs 10 for a purpose hereinafter described.

Mounted upon this supporting member 7 is a frame 11 which is adjustable thereon. Extending through openings in said frame 11 and the supporting member 9 are the rivets or bolts 12. This frame 11 is provided upon the underside thereof with a recess 13 which corresponds to the recess 9 and is also provided with ribs 14 extending parallel with and corresponding in 60 number to the ribs 10.

A roller 15 is positioned in the recess 9 and 14 which may be manipulated for adjustment by means of the thumb nut 16 which extends beyond the end of the supporting member 9 and the frame 11. This 70 roller is provided with longitudinally extending ribs 17 which engage grooves formed between the ribs 10 and 14.

Mounted in suitable bearings formed in the frame member 11 is a roller 18, the peripheral face of which has longitudinally extending grooves 19 which grooves provide a roughened surface forming better contact with the surface of the face when the razor is not used. This roller is also 80 provided with a plurality of circumferentially extending grooves 20. The ends 21, 22 of the roller present cam surfaces as shown more clearly in Figs. 2 and 4. Corresponding cam surfaces are provided in 85 some of the grooves 20 formed in the peripheral face of the roller.

Pivotedly mounted upon the end of the frame 11 is a retaining member 23. This member 23 is preferably formed of two 95 sides extending at right angles to each other as shown in Figs. 1 and 5. The top portion of this retaining member is provided with the ribs 24 extending lengthwise thereof.

25 is a razor blade designed to be used with this construction, which is rectangular in shape and is provided with an elongated opening through the body thereof as shown in Fig. 3.

27 is the shaving edge of the blade which 100 rests upon the guard teeth 8 when in position for use, the opposite edge of the blade

being provided with longitudinally extending grooves 28 which are engaged by the ribs 24 formed on the underside of the retaining member 23.

5 Formed integrally with the blade 25 and projecting into the recess 26 are a plurality of fingers 29, which, when the blade is in operative position project into the grooves, 20, shown more clearly in Fig. 2.

10 Attached to each end of the frame member 11 is a clip 30 which is bent over the edge of the blade 25 to retain the same in position. The cam surfaces 21—22 of the roller 18 contact with the inner edges of 15 the opening 26 of the razor blade 25.

In operation the surface of the roller 18 contacts with the face and in moving the same, a reciprocating movement is transmitted to the blade 25 through the fingers 20 which are positioned within the circumferential grooves 20. The cutting edge 27 of the blade may be adjusted by turning the roller 16 which moves the frame 11 on the supporting member 9 which will adjust 25 the blade with respect to the guard fingers 8 in any relative position required. When it is desired to remove the razor blade 25, the clips 30 are turned out of contact with the blade, and the retaining member 23 30 raised out of engagement with the blade when it can be removed from its place.

I claim—

1. In a safety razor, the combination of a supporting member rigidly mounted upon 35 the handle of the razor, an adjustable frame carried by said supporting member,

a roller having circumferential grooves therein, a blade having an elongated opening therethrough, fingers formed integrally with said blade and projecting into the 40 grooves on the roller, retaining fingers engaging said blade, and means for imparting a reciprocating motion to the razor blade.

2. In a safety razor, the combination of 45 a supporting member rigidly mounted upon the handle of the razor and extending at an angle thereto, said member having guard teeth arranged on one edge thereof, an adjustable frame carried by said supporting 50 member, a roller having circumferential grooves therein, a blade having an elongated opening therethrough, means on said frame for engaging said blade and maintaining it in position, means for adjusting 55 said blade with respect to the aforesaid guard teeth, and means for imparting a reciprocating motion to said blade.

3. In a safety razor, the combination of 60 a supporting member, a frame movably mounted thereon, a retaining member pivotally mounted in said frame, a razor blade having one edge thereof engaged by the aforesaid retaining frame, said blade having an opening therethrough, a roller mounted 65 in the aforesaid frame and extending into said opening and means on said roller for imparting a reciprocating motion to the blade.

In testimony whereof I have signed this 70 specification.

JOHN L. KING.
